ADJUSTABLE SUPPORTING DEVICE

John W. Dollison, Newcomerstown, Ohio

Application May 5, 1941, Serial No. 391,989

4 Claims. (Cl. 248—353)

This invention relates to adjustable supporting devices and its general object is to provide a device in the form of a prop that is primarily designed for clotheslines or the like, and which can be adjusted as to height, in an easy and expeditious manner, yet is held in any adjusted position, against any possibility of casual adjustment or relative movement of the parts, thus assuring a positive supporting function with a maximum load.

An important object is to provide a supporting device for any suitable purpose, that includes at least two elongated sections connected together for longitudinal slidable movement, and novel locking means for normally holding the sections against relative movement, the locking means being mounted on one section and associated with the other section to set up a wedging and biting action therewith.

A further object is to provide a supporting device of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a side elevation of my supporting device constructed in the form of a clothesline prop, with parts broken away and in section, and illustrates the locking means in normal or locked position.

Figure 2 is a fragmentary view somewhat similar to Figure 1, but illustrates the locking means in released position.

Figure 3 is a front view of the device.

Figure 4 is a sectional view taken approximately on line 4—4 of Figure 1, looking in the direction of the arrows.

Figure 5 is a sectional view taken approximately on line 5—5 of Figure 1, looking in the direction of the arrows.

Figure 6 is a perspective view of the locking wedge member.

Referring to the drawing in detail, it will be noted, as above set forth, that I have illustrated my supporting device as being in the form of a clothesline prop, but I want it understood that the important feature is the lock construction and its association with two slidably connected sections, for use as a support, brace or strut, and that the device is not essentially a clothesline prop.

In any event, the structure shown includes an

elongated base or lower section 1 and an elongated upper section 2, both being of cross sectional rectangular shape in the form shown, but they may be of any cross sectional shape, providing each includes at least one flat longitudinal face, preferably for the entire length thereof. The sections 1 and 2 are connected together in face to face relation by substantially U-shaped strap collars, there being two collars 3 fixed to the lower section in spaced relation to each other adjacent to the upper end thereof, with the upper section slidably mounted therein and one collar 4 fixed to the upper section adjacent its lower end for slidable movement on the lower section. By that construction, it will be seen that the upper section 2 is adjustable longitudinally on the lower section 1, to vary the length of the prop and that the collar 4 is engageable with the lowermost collar 3 to limit upward movement of the upper section, so as to prevent removal thereof from the upper end of the lower section.

The upper section has a notch 5 in its upper end that provides a seat for receiving a clothesline, and a notch is preferably outwardly flared toward its upper end to facilitate the insertion of the line therein. The lower section is preferably reduced at its lower end to provide ground penetrating means 6, and while the opposite or inner ends of the sections are shown as being flat, they may be beveled, with the sharp edges of the bevel innermost, as will be apparent.

The locking means for normally holding the upper section 2 in adjusted position against movement relative to the lower section 1 includes a substantially wedge shaped block 7 that is slidably mounted with its thick end uppermost in a wedge shaped recess 8 in the lower section adjacent to the upper end thereof, the recess opening through the inner face of the lower section with its inclined wall 9 extending from said face, as best shown in Figures 1 and 2, and the recess is of ample length and depth to allow for free sliding movement of the flat inner face of the block on the inclined wall 9, for disposal of the inclined outer face of the block into and out of wedging engagement with the inner face of the upper member to lock and release the latter, as will be apparent. The wedge member or block is preferably provided with a cross sectional substantially V-shaped groove 10 extending transversely of the outer face thereof to provide relatively sharp upper and lower edges that tend to bite the upper section for cooperation with the wedging action to prevent movement thereof.

The wedge member is moved to locked and released positions by a hand lever 11 that includes an arcuate inner portion 12 extending through and pivoted in a slot 13 that opens into the recess 8 and through the outer face of the lower mem-

ber, as best shown in Figure 1, and the wedge member is provided with a slot 14 extending along the vertical center thereof and within which is mounted the inner end of the arcuate portion that sets up a camming action on the upper and lower walls of the slot to bring about the sliding movement of the wedge member in its recess, from and to its locked and released positions. The pivot pin 15 for the hand lever extends through the slot 13 and the arcuate portion 12, as best shown in Figure 5 and the lever outwardly of the arcuate portion is straight to provide a convenient hand gripping portion.

The wedge member is held in normal locked position against the upper section by a coil spring 16 that has one end connected adjacent to the upper end of the lower section by suitable fastening means, such as a screw 17, and the opposite end of the spring is connected to a shouldered upper portion formed on the lever, so that the spring will constantly exert an upward pulling action upon the lever for normally urging and holding the wedge member in its locked position, as clearly shown in Figure 1.

From the above description and disclosure in the drawing, it is believed that the operation of my supporting device or prop as shown, will be obvious, but it might be mentioned that when it is desired to adjust the height thereof, the wedge member is released from the upper section, merely by moving and holding the hand lever downwardly against the action of the spring 16. The upper section is then moved to the desired adjusted position, and thence the lever is released for restoring the wedge member to its normal locked position. When so positioned, it will be further obvious that movement of the upper section relative to the lower section is practically impossible, due to the combined wedging and biting action of the wedge member against the upper section.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A supporting device comprising a pair of elongated sections, means connecting the sections together in face to face engagement for relative longitudinal slidable movement to vary the length of the device, one of said sections having a recess therein opening through the inner face thereof, a wedge member slidably mounted in the recess to set up a wedging action on the other section to hold the sections against relative movement, a hand lever connected to the wedge member for moving the latter to locked and released positions, and a spring connected to the recessed section and the hand lever to urge and hold the wedge member in locked position.

2. A supporting device comprising a pair of elongated sections, collars fixed to and connecting the sections together in face to face engagement for relative longitudinal slidable movement to vary the length of the device, one of said sections having a wedge shaped recess therein

opening through the inner face thereof and being provided with an inclined inner wall, a wedge member slidably mounted on the inclined wall and having sharp edges for said member to set up a wedging and biting action on the other section to hold the sections against relative movement, said wedge member and recessed section having slots therein registering with the recess, a hand lever extending into and pivoted in the slot of the section and mounted in the slot of the wedge member for moving the latter to locked and released positions, and a spring connected to the recessed section and the hand lever to urge and hold the wedge member in locked position.

3. A supporting device in the form of a prop for clotheslines, comprising upper and lower elongated sections, means connecting the sections together in face to face engagement for movement of the upper section relative to the lower section, the upper section having a notch in the upper end thereof providing a seat for a clothesline, and the lower section having a beveled lower end providing ground penetrating means, the lower section having a recess adjacent the upper end thereof and opening through its inner face, a wedge member slidably mounted in the recess to set up a wedging action on the upper section to hold the latter against movement relative to the lower section, said wedge member and lower section having slots therein registering with the recess, a hand lever including an arcuate portion extending into and pivoted in the slot of the lower section and mounted in the slot of the wedge member for moving the latter to locked and released positions, said lever having a straight outer portion providing hand gripping means, and a coil spring connected to the lower section and the hand lever to urge and hold the wedge member in locked position.

4. A supporting device in the form of a prop for clotheslines, comprising upper and lower elongated sections, collars fixed to and connecting the sections together in face to face engagement for movement of the upper section relative to the lower section, said upper section having a notch in the upper end thereof providing a seat for a clothesline, said lower section having a reduced lower end providing ground penetrating means, said lower section having a wedge shaped recess therein adjacent its upper end and opening through the inner face thereof, said recess having an inclined inner wall, a wedge member slidably mounted on the inclined wall and having a groove extending transversely in its outer face to provide sharp edges for said member to set up a wedging and biting action on the upper section to hold the latter against movement, said wedge member and upper section having slots therein registering with the recess, a hand lever including an arcuate portion extending into and pivoted in the slot of the lower section and mounted in the slot of the wedge member to set up a camming action for moving the wedge member to locked and released positions, an outer straight portion for the lever and providing hand gripping means, and a coil spring connected to the lower section adjacent its upper end and to the hand lever to urge and hold the wedge member in locked position.

JOHN W. DOLLISON.
